(57) **CLAIM**

The ornamental design for a display screen with graphical user interface, as shown and described.

DESCRIPTION

FIG. 1 is a front view of a display screen with graphical user interface showing an embodiment of my new design; FIG. 2 is a front view of a display screen with graphical user interface showing an embodiment of my new design; FIG. 3 is a front view of a display screen with graphical user interface showing an embodiment of my new design; FIG. 4 is a front view of a display screen with graphical user interface showing an embodiment of my new design; FIG. 5 is a front view of a display screen with graphical user interface showing an embodiment of my new design; FIG. 6 is a front view of a display screen with graphical user interface showing an embodiment of my new design; FIG. 7 is a front view of a display screen with graphical user interface showing an embodiment of my new design; and, FIG. 8 is a front view of a display screen with graphical user interface showing an embodiment of my new design.

The subject matter shown in dashed lines is for illustrative purposes only and forms no part of the claimed design.

The broken lines showing portions of the graphical user interface such as the "X" are included to demonstrate environment and form no part of the claimed design.

The broken lines illustrating the display screen form no part of the claimed design.
